United States Patent Office.

JOSEPH H. SHAW, OF SACO, MAINE.

Letter's Patent No. 65,288, dated May 28, 1867.

IMPROVED PILL MACHINE.

The Schedule referred to in these Letters Patent and making part of the same.

TO ALL WHOM IT MAY CONCERN:

Be it known that I, JOSEPH H. SHAW, of Saco, in the county of York, and State of Maine, have invented a new and useful Improved Pill Machine; and I hereby declare the following to be a full, clear, and exact description thereof, which will enable others to make and use my invention, reference being had to the accompanying drawings forming part of this specification, in which—

Figure 1 shows a top plan of my invention with a portion of the plate *a* broken out in order to show the curved grooves, which are the same in both plates.

Figure 2 is a side elevation of my invention, reduced in scale from fig. 1.

The object of this invention is to make a machine for the rolling of pills, by which, when thus rolled, the pills shall be perfectly, or nearly perfectly, globular. Pills, as now made, are by no means regular in form, or equal in the quantity of medicinal substance embodied in each one. Uniformity of size and regularity of shape are desired in these articles for various considerations of convenience and utility. The reason why pills are so frequently irregular in shape and size is that the pressure in rolling is applied only around a single axis of a pill, thus tending to make it nearer cylindrical than globular in form, and having also the tendency to make the different parts of the pill of different degrees of solidity or density. The only way now used to roll pills, so as to press them upon all sides and all directions upon the circumference, is to roll them in the hand, and thus to manufacture them as nearly as possible of a globular shape. But this is of course a slow process. My method is to arrive at the same result, but with the aid of certain devices, so that economy of time and labor is effected. If two plates with corresponding grooves were placed together and moved backward and forward in a straight line, it is clear that the tendency would be to form a pill of a cylindrical shape, modified only by the curved sides of the grooves. Now, when the grooves are curved the substance to be manufactured into pills, as it is by the opposite motion of the two plates moved around a circle or curve, is revolving around a continually changing axis of motion, thus bringing all parts of the exterior surface of the pill to the pressure of the faces of the two grooves, which will, it is evident, make the pill perfectly round when the pressure is even.

a' a show the two plates with opposing and corresponding grooves, *b. c d* show two arms united with the two plates, as shown in the drawing. In the arm *d* is seen the upright bolt *f*. This bolt passes through the arm *c*, as seen in the drawing.

The method of operating the device is as follows: Place the plate *a* upon the plate *a'*, so that the bolt *f* passes through the end of *c*; grasp *c* with the hand and move *a* backward and forward. The two arms *c-d* represent the radii of a circle, of which the curved plates are segments. As the two plates are swung backward and forward, or around their curve, the pills in the grooves are continually presenting different portions of their surfaces to an equal pressure, and thus are finally shaped into globes. Great celerity and certainty are secured by this device. As the curve is extended the capacity of the machine is increased.

What I claim as my invention, and desire to secure by Letters Patent, is—

The combination of the two curvilinear grooved plates *a a'* united and operated by the two radial arms *c d*, the plate *a* moving upon the stationary plate *a'*, and having for its axis the bolt *f*, all as and for the purposes specified.
